Cecil L. Hopkins, Galion, Ohio

Application May 12, 1954, Serial No. 30,417

Term of patent 14 years

(Cl. D58—26)

Fig. 1

Fig. 3

Fig. 4

Fig. 2

Figure 1 is an elevational view of a combined liquid dispensing and closure cap for bottles showing my new design;

Fig. 2 is a top plan view of the combined liquid dispensing and closure cap for bottles shown in Fig. 1; and

Figs. 3 and 4 are fragmentary sectional details taken substantially along the lines indicated at 3—3 and 4—4 of Fig. 1 and enlarged with respect to that figure to show the shape of the ornamental flutes.

I claim:

The ornamental design for a combined liquid dispensing and closure cap for bottles, substantially as shown.
